BOOK INDEX

William M. Bock, Jr., Milwaukee, Wis.

Application July 3, 1951, Serial No. 235,060

2 Claims. (Cl. 283—42)

1

This invention relates to a book index for enabling a reader to readily locate any desired section or subsection of a book.

Heretofore various book indices have been proposed which have either a plurality of finger-engaging notches formed on the exposed edge of each leaf or sheet of the book, and extensive index provided on one or more leaves located at the front or rear of the book, or a relatively stiff protruding tab fastened to the first page of each of the sections or subsections. The disadvantages of these indices are well known.

In the notched edge type of index, for example, the width of the margin is materially reduced by reason of the notches, thus impairing the use of the margin for notations by the reader. Furthermore, the appearance of the book is impaired by the notched edge sheets, particularly where the book comprises a large number of sections and subsections.

In the second mentioned type of index, the location of a particular section or subsection of the book requires extensive flipping or manipulating back and forth of the pages thereof and at times becomes a frustrating and awkward operation, particularly where it is desired to quickly locate various selected sections or subsections.

The tab-type index is not readily adapted for use in books wherein the sheets thereof are formed of thin tearable paper. In such instances the possibility of the sheets being accidentally torn when the sheets are flipped is greatly enhanced.

Thus, it is one of the objects of this invention to provide a book index which is readily understood and enables a reader to quickly and uninterruptedly locate a desired section or subsection of the book with the least amount of effort.

It is a further object of this invention to provide a book index which does not require notching of the edge of a leaf or sheet, thereby preserving the full width of the margin for notations by the reader.

It is a still further object of this invention to provide a book index which will not impair the appearance of the book.

It is a still further object of this invention to provide a book index which may be readily used with books having the sheets thereof made of very thin tearable paper or other similar type of material without the danger of accidentally tearing the sheets when flipping sheets.

It is a still further object of this invention to provide a book index which is simple to use

2

and may be readily incorporated in any book without materially affecting the printing and binding costs thereof.

Further and additional objects will appear from the description, accompanying drawings, and appended claims.

In accordance with one embodiment of this invention, an index is provided for use in a book having the sheets thereof forming sections and subsections arranged in a predetermined sequence. Provided on the front and back faces of each sheet or leaf of the book is a marginal index. The index comprises a plurality of indicia arranged in columnar relation. The indicia on the front face of a sheet indicates the number and sequence of the book sections that follow the particular sheet; whereas, the indicia on the back face of a sheet indicate the number and sequence of the book sections which precede the particular sheet.

To effect location of a selected book section, relative to an exposed sheet the reader places his finger, normally the thumb, on the edge of the sheet adjacent the margin thereof opposite the indicia which designates the selected section. The sheets preceding or following the exposed sheet, depending upon the case, are then manipulated or flipped by the reader so as to expose the marginal indices thereof, while the thumb remains in the same relative position with respect to the flipped sheets. Where the selected section precedes the exposed sheet the reader flips the preceding sheets until the bottom of the column of indicia on one of the flipped sheets is disposed adjacent the thumb of the left hand of the reader. Where the selected section follows the exposed sheet the reader flips the following sheets until the top of the column of indicia of one of the flipped sheets is disposed adjacent the thumb of the right hand of the reader. When the end of the column of indicia on one of the flipped sheets is positioned adjacent to the thumb of the reader, depending upon the case, the reader knows the selected section has been located and he may then turn directly to it.

For a more complete understanding of this invention reference should be made to the drawings wherein:

Fig. 1 is a front elevational view of a book shown open to one of the early sections thereof.

Fig. 2 is similar to Fig. 1, but shows the book opened to the section thereof indicated by the thumb of the reader's right hand on the margin of the right-hand page shown in Fig. 1.

Fig. 3 is similar to Figs. 1 and 2, but shows the book opened to one of the latter sections thereof.

Referring now to the drawings, a book 10, incorporating the improved book index, is shown grasped between the right and left hands 11 and 12, respectively, of the reader. The book in this instance is the New Testament of the Bible. However, it is to be understood of course that the invention is not to be limited thereto but may be readily incorporated in books such as encyclopedias, dictionaries, reference books, directories, and the like wherein the book is divided into various sections, chapters, classes, etc.

The New Testament 10, as is well known is divided into twenty-seven Books, which for simplicity will hereinafter be referred to as sections. Each of the Books, or sections, of the New Testament is further divided into subsections, called chapters, the number of subsections varying with each section. The New Testament or book 10 is formed of a plurality of relatively thin sheets 13 which are arranged in superimposed relation and assembled or bound along one edge 14 thereof in conventional book form. The flexible sheets are disposed preferably between a flexible protective cover and back 14a and b respectively. Both the front and back surfaces of each sheet in this instance have printed matter thereon. The printed matter is arranged so that a margin 15 is provided on the outer edge of each sheet. The margin 15 is substantially parallel to the bound edge 14. The margins 15 formed on the front and back surfaces 13a and 13b of each sheet are of the same width and length and each has located therein a column of indicia 17 and 18, respectively. Each of the indicia in the column, with the exception of the top indicia in column 17 and the bottom indicia in column 18, is an abbreviation of one of the Books or sections of the New Testament and is referred to as the primary indicia.

In column 17, with the exception of the numeral A which appears at the top thereof and is referred to as a secondary indicia, the remaining or primary indicia indicate the various sections which follow the exposed page or face of a particular sheet, and substantially the sequence or order in which they are arranged. Column 17 extends from the bottom of the page upwardly; however, the order in which the sections occur is determined by reading down the column. The numeral or secondary indicia A at the head of the column denotes the particular subsection of the section which appears on the particular page.

Column 18 positioned on the back face 13b or left-hand page of the sheet, as seen in Figs. 1-3, commences at the top of the margin 15 and extends downwardly and terminates at a point in the margin corresponding to the point where column 17 commences in the margin on page 13a. Column 18, with the exception of the lowermost indicia, is formed of primary indicia designating the various sections which precede the page and the order in which they occur. The relative location of the various sections which precede page 13b is determined by reading up column 18. A numeral B, referred to as a secondary indicia, is positioned at the foot or bottom of column 18 and denotes the subsection which appears on the exposed page—for example in Fig. 1, the 19th Chapter of the Book of the Acts of the Apostles. The relative lengths of columns 17 and 18 vary inversely with respect to one

another as the various sheets of the book are uncovered or exposed. The variations in the relative lengths of columns 17 and 18 are shown in Figs. 1, 2, and 3. In Fig. 1 the book is opened close to the front thereof; in Fig. 2 approximately the center of the book is exposed, and in Fig. 3 the book is opened close to the back portion thereof. The abbreviated indicia of column 17 plus the abbreviated indicia of column 18 indicate all of the various sections of the book with the exception of the particular section which is exposed to the reader.

To locate a particular section and subsection of the book the reader uses the index as follows:

(a) The reader glances at both columns 17 and 18 until he finds the abbreviation for the particular section he is seeking;

(b) Having found the abbreviation of the selected Book, say in column 17, he then places the thumb 20 of his right hand 11 along the edge of the right-hand page 13a adjacent the margin 15 thereof and opposite the location of the selected indicia—the section selected, as shown in Fig. 2 being the Second Epistle of Paul the Apostle to the Thessalonians;

(c) While the thumb 20 is held in this relative position on the edges of the succeeding sheets, they are flipped or manipulated between the thumb 20 and forefinger of the right hand so as to expose the margins thereof until the top of column 17 on one of the flipped sheets is disposed adjacent the thumb 20;

(d) When the top of column 17 is adjacent the thumb 20, the reader continues to manipulate the succeeding sheets until the numeral or secondary indicia A, corresponding to the desired subsection of the selected section, is adjacent the thumb 20 of the reader. As shown in Fig. 2, the reader has selected Chapter 3.

(e) When the desired subsection of the selected section is located the reader may turn directly to it.

If the selected section precedes the exposed left-hand page or sheet, the reader places the thumb 21 of his left hand 12 adjacent the relative position of the abbreviation of the selected section in column 18. The reader then flips or manipulates the sheets between the thumb and forefinger of his left hand, while keeping the thumb 21 in the same relative position, so as to expose the columnated indicia on the flipped sheets. When the numeral or secondary indicia B appears adjacent the thumb 21, the reader knows the selected section has been located and he continues uninterruptedly to manipulate the sheets until the numeral B corresponding to the selected subsection appears adjacent the thumb 21.

Thus, it will be seen that an easy and convenient means has been provided for a reader to readily locate any desired section of the book. The improved book index does not impair the width or length of the margin formed on the front and back surfaces of each sheet and thereby affords ample space for the reader to make marginal notations. Further advantages obtained with the improved book index are that the appearance of the book is not impaired and that the index may be used in books wherein the sheets thereof are formed of very thin, tearable paper or other type of material.

As heretofore mentioned, the improved book index may be readily adapted for use in other types of books such as dictionaries, encyclope-

dias, etc., which have numerous sections and subsections.

While a particular embodiment of this invention is shown above, it will be understood, of course, that the invention is not to be limited thereto, since further modifications may be made, and it is contemplated, therefore, by the appended claims, to cover any such further modifications as fall within the true spirit and scope of this invention.

I claim:

1. A book having a plurality of sections and subsections arranged in a predetermined sequence, comprising a plurality of flexible sheets arranged in superimposed relation and bound together along one edge thereof and having the free edge thereof opposite said bound edge provided with a margin, and an index positioned substantially within said margin on the opposite faces of each sheet; said index comprising a plurality of primary indicia arranged in columnar relation on an exposed face of a sheet and designating all of the book sections disposed behind said exposed face, the column of primary indicia on one face of a sheet commencing at one end of the margin and terminating at a point intermediate the ends of the margin and the column of primary indicia on the opposite face of a sheet commencing at the other end of the margin and terminating at a point in the margin substantially the same as the terminating point of the column on said one face, and secondary indicia disposed at the inner terminating end of the column of primary indicia and designating the subsection appearing on the exposed face of a sheet; said primary indicia being arranged in the column to correspond to the predetermined sequence of the book sections, the primary indicia positioned at the commencing end of the columnated indicia designating the book section disposed farthest behind the exposed face of a sheet.

2. A book having a plurality of sections and

subsections arranged in a predetermined sequence, comprising a plurality of flexible sheets arranged in superimposed relation and bound together along one edge thereof and having the free edge thereof opposite said bound edge provided with a margin, and an index positioned substantially within said margin on the opposite faces of each sheet, and being concealed from view when said book is closed; said index comprising a plurality of primary indicia arranged in columnar relation on the exposed face of a sheet and designating all of the book sections disposed behind said exposed face, the column of primary indicia on one face of a sheet commencing at one end of the margin and terminating at a point intermediate the ends of the margin and the column of primary indicia on the opposite face of a sheet commencing at the other end of the margin and terminating at a point in the margin substantially the same as the terminating point of the column on said one face, and secondary indicia disposed at the inner terminating end of the column of primary indicia and designating the subsection appearing on the exposed face of a sheet; said primary indicia being arranged in the column to correspond to the predetermined sequence of the book sections; the primary indicia positioned at the commencing end of the columnated indicia designating the book section disposed farthest behind the exposed face of a sheet.
